UNITED STATES PATENT OFFICE

164,872

COMBINED WASH BASIN AND CABINET

Jerry T. Mallory, Columbus, Ohio

Application March 31, 1950, Serial No. 8,883

Term of patent 7 years

(Cl. D33—20)

To all whom it may concern:

Be it known that I, Jerry T. Mallory, a citizen of the United States, residing at Columbus, State of Ohio, have invented a new, original, and ornamental Design for a Combined Wash Basin and Cabinet, of which the following is a specification, reference being had to the accompanying drawing, forming a part hereof,

I claim:

The ornamental design for a combined wash basin and cabinet, as shown.

JERRY T. MALLORY.
